United States Patent Office

Des. 179,164
Patented Nov. 6, 1956

179,164

COOKIE JAR

Walter D. Starnes, Los Angeles, Calif., assignor to Walter Starnes, Inc., Los Angeles, Calif., a corporation of California

Application January 9, 1956, Serial No. 39,681

Term of patent 3½ years

(Cl. D58—25)

Fig. 1.

Fig. 2.

Fig. 1 is a perspective view of a cookie jar showing my new design.

Fig. 2 is a side elevational view thereof.

The dominant features of my design reside in the portions shown in full lines.

I claim:

The ornamental design for a cookie jar, substantially as shown and described.
